UNITED STATES PATENT OFFICE

2,001,770

SLICING MACHINE

William J. Campbell, Indianapolis, Ind., assignor
to American Slicing Machine Company, Chi-
cago, Ill., a corporation of New York

Application November 2, 1932, Serial No. 640,784

10 Claims. (Cl. 146—102)

My invention relates to an improvement in slicing machines and has for one purpose the provision of a slicing machine which shall be light, small, and easy to handle but which shall have the efficiency, speed and capacity of considerably larger machines. Another object is the provision of an improved drip pan for use with a slicing machine. Another object is the provision of improved mounting means for a guard plate for a slicing machine.

The present application is a continuation in part of the subject matter of Patent 1,961,959, dated June 5, 1934.

Other objects will appear from time to time in the course of the specification and claims.

I illustrate my invention more or less diagrammatically in the accompanying drawings, wherein—

Figure 1 is a plan view with parts in horizontal section, taken along the line 1—1 of Figure 2;

Figure 2 is a front elevation;

Figure 3 is a section on the line 3—3 of Figure 2;

Figure 4 is a section on the line 4—4 of Figure 2;

Figure 5 is a section on the line 5—5 of Figure 4;

Figure 6 is a detail of the guard plate;

Figure 7 is a partial top plan view with parts broken away;

Figure 8 is a section on the line 8—8 of Figure 2;

Figure 9 is a section on the line 9—9 of Figure 2;

Figure 10 is a section on the line 10—10 of Figure 2; and

Figure 11 is a detail.

Like parts are indicated by like symbols throughout the specification and drawings.

Referring to the drawings, A generally indicates any suitable base having anti-vibrational pads or supports A¹ which rest upon any suitable supporting surface A² for example a counter or the like.

B indicates a motor housing mounted on the base A. B¹ is the motor shaft and B² a pulley on the shaft about which passes a belt B³.

C indicates a housing extension projecting upwardly from the base A. Formed integrally with it is a flared sleeve C¹ terminating rearwardly in a generally cylindrical portion C². Positioned within the portion C², the details of which form no part of the present invention and are not indicated herein, is any suitable bearing means for the knife shaft C³ on which is mounted a pulley

C⁴ and the knife C⁵. As will be seen for example in Figure 1 the pulley is positioned within and is housed by the member C¹ but the cutting edge of the knife C⁵ extends outwardly beyond it as at C⁶, the rear face of the knife being notched or recessed as at C⁷ to receive and overlap the outer edge of the member C¹. Any suitable means may be employed to hold knife and pulley in place, for example the axial screw C⁸ and the radially spaced screws C¹⁰. The knife may be removed from the knife shaft, while leaving the pulley in place, by removing the screw C⁸. The pulley may be removed by loosening the screws C¹⁰. C¹² indicates an end wall of the upward housing projection C and C¹³ the rear wall. As is shown in Figure 1, the rear wall is apertured as at C¹⁴ to permit the passage therethrough of the motor shaft B¹ and of a portion of the motor housing B.

D indicates a shield positioned between the knife transmission and the knife itself. It may seat for example against the inward projection D¹ on the end wall C¹² and it extends well within the periphery of the cutting edge of the knife, preferably approaching the hub of the knife as shown in Figure 1. The inner edge may seat against the ledge D², the member being apertured as at D³ to permit the passage of the hub of the knife therethrough. It may be held in place as by the screws D⁴. It serves as a shield between the knife and the knife transmission, whereby no grease, drippings or scraps can penetrate to the transmission. Since it entirely surrounds the knife, within the periphery of the knife, it will be clear that the centrifugal effect of the rotation of the knife will be to prevent the penetration of any such material sufficiently inwardly toward the axis of rotation of the knife to pass into the aperture D³.

The forward face of the upstanding housing member C is closed as by the guard plate generally indicated as E and shown in detail in Figure 6. As is shown in Figures 1 and 2 the axis of the knife is slightly tilted to permit the arcuate edge E¹ of the guard plate to penetrate a forward hollow E² of the knife and to lie substantially flush with the very slightly bowed cutting plane defined by the cutting edge of the knife. The guard plate carries a scraper E³ secured thereon in any suitable manner, for example by the adjusting screw E⁴. The details of the scraper do not of themselves form part of the present invention. The lower edge of the guard plate is notched as at E⁵ E⁶ to seat upon supporting pins E⁶ which may be screwthreaded for adjustment into the portion of the base or frame to which

they are secured, as shown in Figure 3. Each such pin may include a normally fixed lenticular guard plate engaging member E⁷ and an opposed movable lenticular member E⁷ thrust thereagainst as by the coil spring E⁸. As the opposed faces of the members E⁷, E⁷ are flared apart it will be understood that the guard plate may be readily positioned thereupon, the opposed members having, in response to the action of the spring E⁸ a snap action permitting ready insertion of the guard plate but gripping the guard plate when in position. The upper edge of the guard plate E is provided with ears E⁹ E¹⁰ at right angles to the face of the plate proper such ears overlying top horizontal portions E¹¹ of the frame member C. They are slotted as at E¹² in such fashion that when the plate is swung into the full line position of Figure 3 they pass about the screwthreaded securing pins E²⁰ which hold down the top cover plate G. As will be seen from Figure 6 the ears E⁹ E¹⁰ are of different levels and the guard plate is irregularly formed to permit movement of a knife sharpening assembly which will later be described. The plate E is outwardly offset at top and bottom as at E¹³ E¹⁴ in order to permit the arcuate edge E¹ to penetrate the forward hollow of the knife C⁵. In order to prevent any unintended contact between the guard plate E and the knife, I provide an anti-frictional fiber stud or spacing member indicated as C²⁰ and shown for example in Figures 1 and 2. This anti-frictional stud C²⁰ limits the movement of the guard plate toward the knife and prevents any thrust against the guard plate from causing the guard plate to impinge against the knife. There is normally a clearance between the inner face of the guard plate E and the outer end of the abutment C²⁰, but the parts are so proportioned that a thrust against the face of the guard plate E which might tend to deform it or push it against the knife will bring it into contact, instead, with the abutment C²⁰, thus protecting the knife and preventing the noise which would be caused by a metal to metal contact if the inner face of the guard plate did engage any part of the knife.

The lower edge of the guard plate E is preferably outwardly bent as at E¹⁶, to facilitate its insertion between the engaging members E⁷ when the upper edge of the guard plate is outwardly tilted for convenient insertion. A handle E¹⁷ may be employed for easy handling of the guard plate. In order to permit ready insertion and withdrawal of the ears E⁹ E¹⁰ the top portion E¹¹ of the frame member C and portions of the edge of the cover plate G may be beveled as at E¹⁸. Mounted on one of the horizontal portions E¹¹ of the frame member C is a plate E¹⁹ which is slotted as at E²² to receive an adjusting and locking screw E²¹. The slot E²² being inclined, by moving the member E¹⁹ its forward edge may be adjusted inwardly or outwardly in relation to the guard plate E and serves as a limit to limit the inward movement of the guard plate E to permit its accurate adjustment in relation to the knife. For example it is desired that the arcuate edge of the guard plate penetrate the forward hollow E² of the knife but it is necessary that it does not contact any portion of the knife. Hence the necessity of an accurate adjustment or limit of the inward movement of the guard plate E toward the knife.

In order to assist in locking the guard plate E in position I also provide spring elements E²⁵ with rolled edges E²⁶. When the locking members

E²⁰ are up and the cover plate G is lifted, the springs E²⁵ flex upwardly and permit a ready insertion of the ears E⁹ E¹⁰. When the member E²⁰ is rotated into locking position, then the members E²⁶ serve additionally to hold the guard plate in locked position, as shown in Figure 3. The position of the springs E²⁵ may be adjusted as by means of the adjusting slot E²⁷ and the locking screws E²¹ and E²⁸ passing therethrough.

Positioned on the base, and forwardly of the knife, are the tracks H H¹, the outer tracks H¹ being for example mounted on outwardly extending arms H². Movable along said tracks is a carriage member generally indicated as H³ which includes track engaging members H⁴ H⁵. Mounted on the carriage H³ is the work receiving member which includes a main portion H⁶ downwardly inclined forwardly toward the knife when the parts are in the position shown in Figure 2. At the lower edge is an angle H⁷ at right angles thereto, and with the rounded upper edge portion H⁸. The portion of the member H⁶ adjacent the cutting plane extends outwardly as at H⁹ to terminate in the roller edge H¹⁰. The outer portion terminates as at H¹¹. H¹² indicates a guide pin mounted on the carriage and terminating in a tapered portion H¹³, a rounded enlargement H¹⁴ and a final taper H¹⁵. The maximum diameter of the portion H¹⁴ is substantially the same as the maximum diameter of the body of the pin or shaft H¹².

In order to sharpen the knife I provide a knife sharpening assembly positioned beneath the cover G which includes a unitary lever G¹ with the outer handle G². Mounted along the lever and rotatable in relation thereto is the stone G³ and the metallic burr removing disc G⁴. Yielding means are employed, for example the spring G⁵, for keeping the sharpening lever in intermediate position with the stone and the metal disc both out of contact with the knife edge. The operator may move the lever in either direction, against the pull of the spring G⁵. The plate G is upwardly offset as at G⁶ to give space for the sharpening assembly and is apertured as at G⁷ to permit the lever G² to extend outwardly therethrough. The lever is pivotally supported concentrically with one of the securing members E²⁰. Such member may be surrounded by a bearing sleeve G⁸.

Positioned to the rear of the cutting plane is any suitable slice receiving tray, normally fixed in position, indicated as K. It is upwardly extended at one end as at K¹ and is also upwardly extended forwardly as at K². It may be removed, but is normally locked in position in relation to the slicing machine assembly. The forward edge K² is herein indicated as terminating along a rectilinear horizontal plane as at K³. The flange K² may include an arcuate portion K⁴ conforming generally to the arc of the knife and closely approaching it. K⁵ is an outwardly extending projection from the forward face of the flange K² as illustrated in Figures 2, 5 and 10, the purpose of which will later appear. K⁴ K⁵ are preferably eccentrically formed in relation to the axis of rotation of the knife C⁶, the throat between them increasing progressively in the direction of rotation of the knife. This prevents wedging of the material, as the rotation of the knife tends to move the particles from the narrower to the wider portion of the separating space. Therefore, the material is freed and may drop into the refuse trough.

L indicates a gauge plate support or bracket which extends rearwardly as at L¹ and has a

gauge plate L^2 secured thereto as by the screws L^3 . L^4 is any suitable control lever handle for the gauge plate, the actuating connection not being indicated and forming no part of the present invention.

Generally indicates a refuse or drip pan positioned on the frame A adjacent the lower edge of the knife. I illustrate for example a bottom P^1 which is generally arcuate or rounded in longitudinal vertical section. Referring to its plan view as shown in Figure 4 it has a forward wall P^2 generally rectilinear and a rear wall which includes one portion P^3 adjacent the cutting plane of the knife and another portion P^4 extending substantially inwardly beyond the cutting plane of the knife. The portion P^3 has a generally arcuate edge conforming generally to and closely approaching the periphery of the knife, as will be clear in Figures 2 and 5. The portion P^4 extends inwardly beneath the lower edge of the guard plate E and also extends beneath or adjacent the lower edge of the inner plate D, as will be clear from Figure 3. The plates D and E both terminate above the upper edge of that portion of the wall P^4 which approaches them. The trough may be held in position as by the flanges P^5 , one being positioned adjacent each end of the trough. These flanges P^5 have flat lower faces P^6 which conform to a corresponding flat upper face on the base A. They are apertured as at P^7 to permit the passage therethrough of securing pins P^8 upwardly headed as at P^9 . P^{10} are springs, positioned within or beneath the base A, and compressed between the lower wall of the base A and washers P^{11} , whereby the heads P^9 are normally downwardly drawn against the flanges P^6 . Note that the right hand flange P^5 is slotted in the end, as shown in Figure 4, whereas the left hand flange is slotted in the side. In removing the device it will be clear, as by comparison of the dotted and full line positions of the pan in Figure 4, that the pan may be rotated about the right hand pin P^8 as an axis, until the left hand flange has been withdrawn from operative connection with its corresponding securing pin. Note that the flanges are bevelled as at P^{12} to permit their ready insertion beneath the heads P^9 . Note also that the flange K^5 of the slice receiving member K overlies the inner wall P^3 of the pan, as will be clear from Figure 10. Note also that the pan is aligned beneath the scraper E³ and receives the discharge therefrom and also is positioned to receive whatever material if any may flow down the inner guard plate D.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

The structure herein described and shown forms a light, easily operated and efficient slicing machine of the manual feed type, in which the rotary knife C⁵ is rotated at relatively high speed by electric motor means. The carriage H³ is guided by the tracks H H¹, but the carriage is moved manually by the hand of the operator. Mounted on the carriage for movement along a path preferably at right angles to the cutting plane is the pusher plate J, which is also man-

ually operated. For example, the operator may grasp with his hand the sleeve J⁴, the arm J² or the handle J¹. By thrusting forwardly along the cutting plane and somewhat inwardly toward the cutting plane the work is thrust into effective contact with the forward face of the gauge plate L². A continuation of the inclined thrust carries the carriage and the work, properly gauged, against the cutting edge of the knife C⁵. The slice is cut and falls upon the slice receiving tray 10 K. The work meanwhile continues across the face of the guard plate E until the work has been entirely carried past the cutting edge and the slice has been severed. The operator then manually withdraws the carriage and repeats his 15 inclined thrust for the ensuing stroke and slice.

Ready removal of the guard plate E is important. It can be removed or replaced by merely loosening the screws E²⁰ sufficiently to withdraw the ears E⁹ E¹⁰. The plate is then tilted into the 20 dotted line position of Figure 3, its tilting being readily permitted by the opposed gripping or abutment members E⁷ E⁸. The plate is then upwardly removed and may be similarly replaced.

The refuse pan P is positioned beneath and 25 adjacent the lower portion of the edge of the knife and is positioned to receive any discharge from the scraper E³. As will be clear from Figure 3, it is also in position to receive any discharge or drippings from the forward face of the 30 outer guard plate E and also from the inner guard member D. The projection of the wall P⁴ of the pan beneath the guard plate E and into opposition with the lower edge of the guard D will be clear from Figures 3 and 4. The pan can 35 readily be applied and removed, since it is received and held by spring actuated headed securing pins. The method of removal is indicated in Figure 4, the right hand pin serving as an axis when the pan as a whole is rotated into or 40 out of operative position. After it has been rotated into the dotted line position of Figure 4, it may be withdrawn readily endwise from the remaining pin.

I claim:

1. In a slicing machine including a base, a knife thereon and means for actuating it, and a carriage and means for guiding the carriage past the cutting edge of the knife, a guard plate for the forward face of said knife and a frame portion extending upwardly from said base, adapted to support said guard plate, and means for securing said guard plate on said frame portion, including securing pins adapted to receive the lower edge of said guard plate, a plurality of 55 plate engaging members on said pins, yielding means for thrusting them together against opposite sides of the plate, said members being provided with opposed bevelled faces adapted to permit ready penetration of the guard plate 60 therebetween, said bevelled faces being flared widely apart when said plate engaging members are in contact with each other, and additional means for securing the upper edge of the guard plate.

2. In a slicing machine including a base, a knife thereon and means for actuating it, and a carriage and means for guiding the carriage past the cutting edge of the knife, a guard plate for the forward face of said knife and a frame 70 portion extending upwardly from said base, adapted to support said guard plate, and means for securing said guard plate on said frame portion, including securing pins adapted to receive the lower edge of said guard plate, a plurality of 75

plate engaging members on said pins, yielding means for thrusting them together against opposite sides of the plate, said members being provided with opposed bevelled faces adapted to 5 permit ready penetration of the guard plate therebetween said bevelled faces being flared widely apart when said plate engaging members are in contact with each other, and additional means for securing the upper edge of the 10 guard plate, said guard plate being provided with slots adapted to be penetrated by said securing pins.

3. In a slicing machine including a base, a knife thereon and means for actuating it, and a carriage and means for guiding the carriage past the cutting edge of the knife, a guard plate for the forward face of said knife and a frame portion extending upwardly from said base, adapted to support said guard plate, and means for securing 15 said guard plate on said frame portion, including securing pins adapted to receive the lower edge of said guard plate, a plurality of plate engaging members on said pins, yielding means for thrusting them together against opposite sides of the 20 plate, said members being provided with opposed bevelled faces adapted to permit ready penetration of the guard plate therebetween said bevelled faces being flared widely apart when said plate engaging members are in contact with each other, and additional means for securing the upper edge of the guard plate, including a flange adapted to extend over and engage an upper edge of said frame portion, and a cover plate 25 adapted to overlie said guard plate, and securing means for the cover plate adapted to penetrate the cover plate and guard plate and frame portion.

4. In a slicing machine including a base, a knife thereon and means for actuating it, and a carriage and means for guiding the carriage past the cutting edge of the knife, a guard plate for the forward face of said knife and a frame portion extending upwardly from said base, adapted to support said guard plate, and means for securing 30 said guard plate on said frame portion, a scraper positioned adjacent the lower edge of the guard plate, and opposed to the forward face of the knife, a refuse pan mounted on the base for ready removal therefrom, said pan extending forwardly of the cutting plane on the carriage side thereof, and being positioned in cooperative relation with the scraper and including a wall portion lying closely adjacent and conforming 35 generally to a portion of the periphery of the knife, said refuse pan being forwardly removable from the machine, a portion of said refuse pan extending rearwardly beneath the lower edge of the 40 guard plate.

5. In a slicing machine including a base, a knife thereon and means for actuating it, and a carriage and means for guiding the carriage past the cutting edge of the knife, a guard plate for the forward face of said knife and a frame portion extending upwardly from said base, adapted to support said guard plate, and means for securing 45 said guard plate on said frame portion, including securing pins adapted to receive the lower edge of said guard plate, a plurality of plate engaging members on said pins, yielding means for thrusting them together against opposite sides of the plate, said members being provided with opposed bevelled faces adapted to permit ready penetration of the guard plate therebetween said bevelled faces being flared widely apart when said plate engaging members are in contact with each other, and additional means for securing the upper edge of the guard plate, and a manually 50 engageable handle positioned on the upper portion of the guard plate.

6. In a slicing machine including a base, a knife thereon and means for actuating it, and a carriage and means for guiding the carriage past the cutting edge of the knife, a guard plate for the forward face of said knife and a frame portion extending upwardly from said base, adapted to support said guard plate, and means for securing 55 said guard plate on said frame portion, including securing pins adapted to receive the lower edge of said guard plate, a plurality of plate engaging members on said pins, yielding means for thrusting them together against opposite sides of the plate, said members being provided with opposed bevelled faces adapted to permit ready penetration of the guard plate therebetween said bevelled faces being flared widely apart when said 60 plate engaging members are in contact with each other, and additional means for securing the upper edge of the guard plate, including a flange adapted to extend over and engage an upper edge of said frame portion.

7. In a slicing machine including a base, a knife thereon and means for actuating it, and a carriage and means for guiding the carriage past the cutting edge of the knife, a guard plate for the forward face of said knife and a frame portion extending upwardly from said base, adapted to support the guard plate, and means 65

thereon and means for actuating it, and a carriage and means for guiding the carriage past the cutting edge of the knife, a guard plate for the forward face of said knife and a frame portion extending upwardly from said base, adapted to support said guard plate, and means for securing said guard plate on said frame portion, including securing pins adapted to receive the lower edge of said guard plate, a plurality of plate engaging members on said pins, yielding means for thrusting them together against opposite sides of the plate, said members being provided with opposed bevelled faces adapted to permit ready penetration of the guard plate therebetween said bevelled faces being flared widely apart when said plate engaging members are in contact with each other, and additional means for securing the upper edge of the guard plate, including a flange adapted to extend over and engage an upper edge of said frame portion, and a cover plate 10 adapted to overlie said guard plate, and securing means for the cover plate adapted to penetrate the cover plate and guard plate and frame portion.

8. In a slicing machine including a base, a knife thereon and means for actuating it, and a carriage and means for guiding the carriage past the cutting edge of the knife, a guard plate for the forward face of said knife and a frame portion extending upwardly from said base, adapted to support said guard plate, and means for securing said guard plate on said frame portion, a scraper positioned adjacent the lower edge of the guard plate, and opposed to the forward face of the knife, a refuse pan mounted on the base for ready removal therefrom, said pan extending forwardly of the cutting plane on the carriage side thereof, and being positioned in cooperative relation with the scraper and including a wall portion lying closely adjacent and conforming 15 generally to a portion of the periphery of the knife, said refuse pan being forwardly removable from the machine, a portion of said refuse pan extending rearwardly beneath the lower edge of the 20 guard plate.

9. In a slicing machine including a base, a knife thereon and means for actuating it, and a carriage and means for guiding the carriage past the cutting edge of the knife, a guard plate for the forward face of said knife and a frame portion extending upwardly from said base, adapted to support said guard plate, and means for securing 25 said guard plate on said frame portion, a scraper positioned adjacent the lower edge of the guard plate, and opposed to the forward face of the knife, a refuse pan mounted on the base for ready removal therefrom, said pan extending forwardly of the cutting plane on the carriage side thereof, and being positioned in cooperative relation with the scraper and including an arcuate 30 wall portion lying closely adjacent and conforming generally to a portion of the periphery of the knife, said pan including a portion remote from the knife, extending substantially inwardly beyond the cutting plane, said arcuate edged wall portion lying substantially in the cutting plane, said refuse pan being forwardly removable from the machine, a portion of said refuse pan extending rearwardly beneath the lower edge of the 35 guard plate.

10. In a slicing machine including a base, a knife thereon and means for actuating it, a guard plate for the forward face of said knife, and a frame portion extending upwardly from said base, adapted to support the guard plate, and means 40

for securing said guard plate on said frame portion, an additional guard member on said frame portion, positioned to the rear of the guard plate, and a refuse pan mounted on the base for ready removal therefrom, said pan underlying said guard plate and said additional guard member, and the space therebetween, said refuse pan including a rear wall generally aligned vertically with and extending beneath the lower edge of

10 said additional guard member.

10. In a slicing machine including a base, a knife thereon and means for actuating it, a guard

plate for the forward face of said knife, and a frame portion extending upwardly from said base, adapted to support the guard plate, and means for securing said guard plate on said frame portion, and a scraper, opposed to the edge portion of the knife, said scraper being mounted upon said guard plate, the guard plate including portions projecting from its general plane, said projecting portions being positioned above and below said scraper and being adapted to limit its 10 rotation when in normal operative position.

WILLIAM J. CAMPBELL.
